CURTAIN STRETCHER

Noble M. Mavity, Detroit, Mich.

Application June 6, 1934, Serial No. 729,198

7 Claims. (Cl. 45—24)

The invention relates particularly to an apparatus for and method of stretching curtains.

One object of the invention is to provide an improved curtain stretcher which enables stretching curtains uniformly at all points along their ends and sides so as to obtain straight edges.

Another object of the invention is to provide a curtain stretcher which is particularly adapted to stretch curtains and obtain straight end and side edges wherein the curtains have hems at their sides and also at their ends.

Another object of the invention is to provide a method of stretching curtains having hems at both the ends and sides so as to obtain straight side and end edges.

Other objects of the invention will become apparent from the following description, the drawing relating thereto and from the claims herein-after set forth.

For a better understanding of the invention, reference may be had to the drawing, wherein:

Figure 1 is a plan view of a curtain stretcher constructed according to one form of the invention.

Fig. 2 is a cross-sectional view on a larger scale taken substantially along the line 2—2 of Fig. 1.

Fig. 3 is a cross-sectional view on a larger scale taken substantially along the line 3—3 of Fig. 1.

Fig. 4 is a cross-sectional view on a larger scale taken substantially along the line 4—4 of Fig. 1.

Fig. 5 is a cross-sectional view on a larger scale taken substantially along the line 5—5 of Fig. 1.

Fig. 6 is a fragmentary view illustrating use of the curtain stretcher in connection with another type of curtain.

The curtain stretcher illustrated is particularly adapted to stretch a curtain indicated at 10 which has hems 11 at its ends as shown in detail by Fig. 5, and hems 12 at its sides as shown in detail by Fig. 4. Generally and as shown in the curtain illustrated, the side hems 12 are formed first by folding over side edges of the curtain material and then stitching along the folded edge and following this, end portions of the curtain material are folded over and stitched to provide the end hems 11.

Pursuant to this practice, the side hems 12 are closed at their ends when the material is folded over in forming the end hems but the latter have their ends open.

The stretcher includes bars 14 that are inserted endwise through the end hems 11 until the ends of the bars project beyond both sides of the curtain and, owing to the size of the hems usually employed, the bars 14 may have sufficient dimensions that they provide a rigid means for stretch-

ing the curtain endwise. For stretching the side edges of the curtain, small wire-like rods 15 are employed and these rods have substantially pointed ends as indicated at 16. In practically all instances the curtain material is of open mesh character and the rods 15 with their pointed ends 16 are of such size that the material may be pierced with the rods without actual tearing of the material. One of these rods then is inserted from one end of each of the side hems 12 and in inserting the rod the pointed end thereof is passed through that portion of the end hem 11 at the end of the side hem. The rod is passed over or under the bar 14 and then through the side hem until the inserted end of the rod is at the other end of the curtain where the rod then is passed over or under the other bar 14 and its pointed end is pierced through the other end hem 11. When one of the rods 15 has been inserted in this manner in each of the side hems 12, the curtain is in condition to be stretched.

It may be mentioned also that the rods 15 pass through stitch loops of the stitching that holds the end hems 11 across the side hems 12. It follows that when the curtain is stretched laterally, this stitching is also drawn laterally, thereby avoiding puckering that otherwise might occur owing to the tendency of the stitching to hold the curtain material against stretching. The size of the rods 15 and the pointed ends thereof readily facilitate passing the rods through the stitch loops.

For stretching the curtain a frame is provided which includes end bars 18, a side bar 19 rigidly connected to the ends of the end bars 18 by means of angle brackets 20 and an adjustable side bar 22. It may be mentioned that the angle brackets 20 provide a rigid means for maintaining the shape of the frame and this is important during the curtain stretching operation. Each end of the side bar 22, as best shown by Fig. 2, is provided with plates 23 and 24 at its opposite sides, and these plates are secured to the bar by means of screws 25 or the like. The ends of the plates project beyond the ends of the bar 22 and are bent into converging relation as indicated at 26 and such converging ends of the bars receive the end bars 18. A bolt 27 having a wing nut 28 extends through each end of the bar 22 and through the plates 23 and 24 and the plates are slightly bulged where the bolts project through them so that by tightening the wing nut 28 a clamping action is obtained which draws the converging ends 26 of the plates into tight engagement with the end bar 18. By loosening the wing nut 28 the plates 23 and 24 are moved apart so that the end bars 18 may be inserted through the plates and the side bar 19 may be moved to the side of the curtain to facilitate stretching the curtain.

wing nuts 28 the bar 22 may be moved inwardly or outwardly so as to increase or decrease the size of the frame and after adjustment tightening of the wing nuts 28 serves to hold the bar 22 rigidly in position.

In stretching the curtain endwise one of the bars 14 may be fastened to the side bars 15 and 22 and then the other bar 14 may be pulled to stretch the curtain, after which the latter bar is held in adjusted position. For so holding the bars, a series of openings 30 may be provided longitudinally in each of the side bars 15 and 22 and nails or other suitable elements adapted to fit selectively in these openings may be used for holding the bars in place. In the construction illustrated nails 31 are shown as piercing the upper ends of the bars disposed over the frame bar 15 and projecting into certain of the openings 30, whereas on the bar 22 one of the nails 31 is shown at the inner side of the bar 14 and a bracket screw 33 as shown by Fig. 2 is provided for holding the end of the other bar 14. Any other suitable means may be used for holding the bars 14 in position during the time that the curtain is to be held in a stretched condition and which permits adjustment of bar 22. It will be appreciated that the end edges of the curtain will be maintained straight owing to the contact of the bars 14 all along the end hems 11. The wire-like rods 15 necessarily are flexible and particularly so when the length of the ordinary curtain is considered as the rod must be sufficiently small to pass through the mesh without tearing the threads. For holding the side edges of the curtain to the frame members 15 and 22, more rigid rods 34 may be mounted on each of the bars 15 and 22 and these rods are shown as passing through eye elements 35 disposed at spaced points along the bars. The ends of the rods may project through bracket plates 36 and have heads on their ends so that the rods will not move lengthwise. As shown best by Fig. 4, each of the rods 34 is provided with a series of pincher-like fastener elements 37 and each element as illustrated comprises gripping members 38 and 39 having complementary notches in their adjacent surfaces for receiving a coil spring 40 which encircles the rod and is slidable thereon. One end of this spring extends along the pincher element and seats in a notch 41 in one of the members 39 and the other end of the spring seats in a notch in the member 38. The right ends of the members 38 and 39 have notches 42 adapted to grip over the side hems 12 and to the edge portions of the hems in which the rods 15 are disposed.

By having these pincher members at suitably spaced points along the rod 34 it will be appreciated that the length of the rod 15 between any two of the pincher members may be sufficiently short that it possesses sufficient rigidity to pull substantially uniformly on the edge of the curtain between such members. After the side edges of the curtain have been engaged with the several pincher members 37 on each of the frame members 15 and 22, the frame member 22 is pulled in such manner as to stretch the curtain and then the wing nuts 28 are tightened so as to hold the frame member in position. It is apparent of course that the curtain may have been stretched previously in a longitudinal direction or such stretching of the curtain may be effected after adjustment of the frame member 22 to stretch the curtain laterally and it will be appreciated that the holding means on the frame

member 22 for maintaining the bars 14 in stretched relation does not interfere with adjustment of the frame member.

After the curtain has been maintained in a stretched condition for a proper period of time, the frame member 22 may be released and the nails 31 removed holding the bars 14 and following this the bars may be removed from the end hems 11. The pincher members 37 may then be released from gripping engagement with the side hems 12 and the rods 15 then pulled out of the hems. While the mesh openings through which the rods 15 project in the ends of the hems 11 may be slightly enlarged, this can be readily corrected so as to reduce the enlargement by pressing the curtain material with an iron or the like.

The curtain thus treated has perfectly straight side edges as well as end edges and actual practice of the invention has revealed it to be highly efficient. No damage to the curtain is done by passing the rods 15 through the material owing to the smallness of their size and in conjunction with the pincher members 37 and the rigid rod 34, an efficient and positive means is provided for applying uniform stretching to the side edges throughout their length.

Fig. 6 illustrates use of the stretcher in connection with a curtain of the shadow lace type wherein a folded fabric bead 45 or the like of scalloped character is provided along the side edges and the ends have hems such as previously described. In mounting this curtain within the frame and stretching it, the bars 14 may be employed in conjunction with the end hems and the rods 15 are passed through the outer scalloped portions of the beads 45. It will be noted that the rod first passes over the bead, then under the bead at two points, then over the bead at two points, etc., so that such outer scalloped portions are caught by the rod. The curtain then may be stretched on the frame as previously described, although in this case the members 37 will more or less directly engage the rods 15.

Although only one form of the invention has been illustrated and described in detail, it will be apparent to those skilled in the art that various modifications may be made without departing from the scope of the appended claims.

I claim:

1. The method of stretching curtains having a hem along each edge wherein two opposed hems are closed at their ends, which comprises passing bars through the other opposed hems, piercing the curtain material at the closed ends of the first hems by means of small wire-like rods and passing such rods through such hems and over the ends of the bars, stretching the curtain in one direction by moving the bars farther apart, and stretching the curtain in the other direction by gripping the hem portions enclosing the wire-like rods at a plurality of points along the edges of the curtain.

2. The method of stretching curtains having a hem along each edge wherein two opposed hems are closed at their ends, which comprises passing bars through the other opposed hems, piercing the curtain material at the closed ends of the first hems by means of small wire-like rods and passing such rods through such hems, releasably fastening the hem portions enclosing the wire-like rods at a plurality of points to provide substantially rigid elongated members and then stretching the curtain by moving the bars apart in one direction and the rigid members apart in the transverse direction.

3. The method of stretching fine mesh curtains having a hem along each edge wherein two opposed hems are closed at their ends by the folded over portions forming the other opposed hems, 5 which comprises passing bars through the latter opposed hems, inserting small wire-like rods through the first opposed hems by enlarging mesh openings in the material at the closed ends of such hems, stretching the curtain by spreading 10 the rods and bars in transverse directions, removing the rods and bars and then reducing such enlarged mesh openings substantially to the normal size thereof.

4. A curtain stretcher for stretching mesh curtains having a hem at each edge wherein one pair of opposed hems are closed at their ends, which comprises substantially stiff bars adapted to pass through the other pair of opposed hems, flexible, 15 small wire-like flexible rods adapted to pass through the other opposed hems and through mesh openings in the material at the closed ends of the hems, means for holding the bars in position after stretching the curtain by moving such bars farther apart, relatively rigid means extending along the hems having the wire-like rods therein, and means connected to said rigid means for gripping the latter hems around the wire-like rods at a plurality of points along said rods, 20 whereby the wire-like rods may be rendered sufficiently inflexible between said points as to apply stretching forces in a substantially uniform manner along the hems in which such rods are disposed.

5. A curtain stretcher for stretching mesh curtains having a hem at each edge wherein one pair of opposed hems are closed at their ends, which comprises substantially stiff bars adapted to pass through the other pair of opposed hems, flexible, 25 small wire-like flexible rods adapted to pass through the other opposed hems and through mesh openings in the material at the closed ends of the hems, means for holding the bars in position after stretching the curtain by moving such bars farther apart, relatively rigid means extending along the hems having the wire-like rods therein, and means connected to said rigid means for gripping the latter hems around the wire-like rods at a plurality of points along said rods, 30 whereby the wire-like rods may be rendered sufficiently inflexible between said points as to apply stretching forces in a substantially uniform manner along the hems in which such rods are disposed.

6. A curtain stretcher for stretching mesh curtains having a hem at each edge wherein one pair of opposed hems are closed at their ends, which comprises substantially stiff bars adapted to pass through the other pair of opposed hems, flexible, 5 small wire-like flexible rods adapted to pass through the other opposed hems and through mesh openings in the material at the closed ends of the hems, means for holding the bars in position after stretching the curtain by moving such 10 bars farther apart, relatively rigid means extending along the hems having the wire-like rods therein, and means connected to said rigid means for gripping the latter hems around the wire-like rods.

6. A curtain stretcher for stretching mesh curtains having a hem at each edge wherein one pair of opposed hems are closed at their ends, which comprises substantially stiff bars adapted to pass through the other pair of opposed hems, flexible, 15 small wire-like flexible rods adapted to pass through the other opposed hems and through mesh openings in the material at the closed ends of the hems, means for holding the bars in position after stretching the curtain by moving such 20 bars farther apart, relatively rigid means extending along the hems having the wire-like rods therein, and means connected to said rigid means for gripping the latter hems around the wire-like rods at a plurality of points along said rods, 25 whereby the wire-like rods may be rendered sufficiently inflexible between said points as to apply stretching forces in a substantially uniform manner along the hems in which such rods are disposed, said relatively rigid means comprising rods 30 and said gripping means comprising pincher means mounted on and adjustable along the rods.

7. A device for stretching curtains wherein the curtain has one pair of opposed hems closed at the ends and the other pair open at their ends, 30 comprising a rectangular frame having opposed sides, one of which is adjustable to increase the size of the frame, bars extending transversely of said opposed sides of the frame and adapted to pass through the hems open at their ends, means 35 on the opposed sides of the frame for adjustably holding the ends of the bars in curtain stretching position without interfering with adjustment of the adjustable frame member, small wire-like flexible rods adapted to pierce the curtain material at the ends of the other hems and to be disposed in such hems, and a plurality of means mounted on said opposed sides of the frame and at spaced points therealong for gripping the upper and lower sides of said other hems and about 40 the rods therein whereby the rods between each pair of said gripping means are rendered substantially rigid for the purpose of applying substantially uniform stretching forces at all points 45 along said other hems.

NOBLE M. MAVITY.
